ONE-PIECE BUCKLE

Paul W. White, Fort Lauderdale, Fla., assignor
to Parva Products Company, Chicago, Ill., a
corporation of Delaware

Application May 17, 1943, Serial No. 487,227

11 Claims. (Cl. 24—193)

This invention relates to buckles, more particularly to one-piece buckles formed of molded plastics or similar nonmetallic materials, and the invention has for an object the provision of a simple, rugged and reliable buckle of this character.

In the past various attempts have been made to provide a satisfactory one-piece buckle capable of easy adjustment and of securely holding a strap, belt or the like in any desired adjusted position. The difficulties of combining ease of adjustment with security against slippage, however, have resulted either in constructions requiring complicated and bulky threading arrangements, in the use of sharp prongs or spikes which inevitably tear and injure the belt or strap, or in recourse to the well known pivoted prong or slide type two-piece buckles.

With the advent of recent metal shortages and restrictions, which make highly desirable the adoption of substitute materials, such as moldable plastics and the like, in lieu of metals, the advantages of providing a one-piece buckle have increased immeasurably. At the same time, however, due to the decreased strength of materials of this character, the problems involved in providing small, flat, one-piece buckles, which are inexpensive to construct and easy to thread and which will not slip when subjected to tension, involve even greater difficulties. It is not thought that any entirely satisfactory construction has heretofore been provided, and accordingly it is a further object of this invention to provide a one-piece plastic buckle of pleasing appearance which, when applied to a strap, does not cause excessive bulging, which may be inexpensively manufactured in any desired quantities, and which may readily be manipulated to permit ready adjustment and to secure the strap in desired adjusted positions.

In carrying out the present invention, a combination of features is employed which co-operates in a novel manner to provide a rugged construction, ease of threading and adjusting, and a high degree of resistance to slipping. Strength and ruggedness of the one-piece buckle is achieved by providing a frame having strong, thick side bars of greater thickness than the strap, and crossbars of lesser thickness selectively inset either from the front or the rear surfaces of the side bars, so that the strap, when threaded, lies at least partially within the confines of the side bars thereby avoiding excessive bulging. Ease of threading is obtained by employing a simple co-operative relation between the bars

and the strap which does not involve complicated or multiple interwinding of the strap through the buckle, so that when tension is released the free end of the strap may be readily drawn through the slots of the frame, the bars and slots at the same time being so arranged and so shaped that upon the application of tension to the strap slipping of the strap relative to the frame is resisted by distortion of the strap in a plurality of directions, by frictional resistance between overlying portions of the strap, and by clamping a portion of the strap against a broad clamping surface of the frame.

For a more complete understanding of the invention reference should now be had to the drawings, in which:

Fig. 1 is a perspective view of a one-piece buckle frame preferably formed of molded plastic material and embodying the present invention;

Fig. 2 is a front view of the buckle shown in Fig. 1 in association with a suitable strap or belt;

Fig. 3 is a sectional view taken substantially along the line 3—3 of Fig. 2;

Fig. 4 is a perspective view of another one-piece buckle embodying the present invention;

Fig. 5 is a front view similar to Fig. 2 showing the buckle of Fig. 4 associated with a strap;

Fig. 6 is a sectional view taken along the lines 6—6 of Fig. 5;

Fig. 7 is a perspective view of another one-piece buckle embodying the present invention;

Fig. 8 is a sectional view taken substantially through the center line of the buckle shown in Fig. 7 and illustrating the association of this buckle with a strap; and

Fig. 9 is a front plan view of still another one-piece buckle embodying the present invention.

Referring now to Figs. 1, 2 and 3 of the drawing, the invention is shown as embodied in a one-piece buckle comprising a frame formed of molded plastic and having a pair of spaced apart side bars 10 and 11 which, as shown best in Fig. 3, are of considerably greater thickness than the thickness of the strap or belt. The side bars 10 and 11 are connected by end bars 12 and 13 and by intermediate crossbars 14 and 15, so as to define a plurality of strap-receiving slots 16, 17, and 18.

As shown best in Figs. 1 and 2, the inner side walls of the end bars 12 and 13 are curved in opposite directions and, as shown best in Fig. 3, the rear walls of the end bars 12 and 13 are inset from the rear surfaces of the side bars 10 and 11.

a distance substantially equal to the thickness of the strap or belt. The rear wall of the end crossbar 12 meets the curved side wall of this end bar in a sharp edge 19 (Fig. 3), while the rear wall of the end bar 13 gradually merges into the curved side wall of this end bar to provide a broad, sloping clamping surface 20.

In order to provide for transverse curvature or distortion of the strap when it is threaded through the buckle frame, the intermediate crossbar 14 is provided with a curved side wall which is spaced from the curved side wall of the end bar 12 so as to provide the elongate arcuate slot 16 extending across the buckle frame. The front wall of this intermediate crossbar 14, as shown in Figs. 1 and 3, is inset from the front surfaces of the side bars 10 and 11 and meets the curved side wall of the bar 14 in a sharp edge.

The second intermediate crossbar 15 is spaced from the other edge of the intermediate crossbar 14 to provide the slot 17 which is of a width only slightly greater than the thickness of the strap with which the buckle frame is to be associated, and is spaced from the end wall 13 a sufficient distance so that the slot 18 is adapted to receive plural thicknesses of the strap. As shown, the front wall of the intermediate crossbar 15 is inset from the front surfaces of the side bars 10 and 11 a distance substantially equal to the thickness of the strap and somewhat greater than the inset distance of the intermediate crossbar 14.

Although buckles embodying the present invention may be associated with various straps or similar articles, and in fact are capable of universal application wherever detachable fastenings are desired, the embodiments of the invention herein shown are intended particularly for use with belts, or straps such as wrist-watch straps, adapted to encircle a portion of the body of the wearer. In the drawing, the strap or belt is shown as comprising an attaching portion 21 which constitutes one end of the belt, and an adjusting portion 22 which terminates in a free end 23. At its extreme end the attaching portion 21 is thickened, as shown, by sewing or otherwise securing thereto a strip of material 24 which may be of the same material as the belt or strap, and the lower wall of the crossbar 14 is notched out, as shown, to provide a recess for this thick end portion. Of course, the thick end on the attaching portion 21 may be formed in any desired manner, as by doubling over the end of the strap or by securing a metal clip thereto.

To attach the buckle to the strap, it is necessary only to insert the strap through the slot 17 and pull it entirely therethrough until the thick end portion 24 engages the notch in the crossbar 14 and prevents further movement of the strap through the slot. The strap may then be passed over the upper surface of the crossbar 15 and rearwardly through the wide slot 18, and after the strap has been passed around the body portion of the wearer, the free end 23 may be passed through the curved slot 16 from the rear to the front of the buckle and pulled therethrough until the strap reaches the desired adjusted position. To secure the strap in this position, it is necessary only to pass the free end rearwardly through the wide slot 18 so that it overlies the attaching portion 21 and extends between this attaching portion and the rear wall of the end crossbar 13.

If tension is now applied to the two portions of the strap in the respective directions indicated

by the arrows 25 and 26, it will be apparent that the adjusting portion of the strap will be tightly clamped between the rear wall of the end crossbar 13 and the underlying adjusting portion 21 of the strap. At the same time, the two portions of the strap will be pressed tightly into frictional engagement with each other and the part of the adjusting portion 22 which passes through the curved slot 16 will be sharply bent over the curved front edge of the intermediate bar 14 and the curved rear edge of the end bar 12. This sharp bending of the strap occurs at the part thereof which is transversely curved by the walls of the slot 16, and the resulting distortion of the strap, coupled with the frictional forces and the clamping action beneath the end bar 13, insures that the free end of the strap will not pull through the buckle frame and in fact prevents any slipping movement of the adjusting portion 22 relative to the buckle frame.

Upon release of the tension, the buckle may readily be adjusted, since the clamping and frictional forces will immediately be released, and the adjusting portion of the strap may then readily be pulled through the curved slot 16 to a new adjusted position. The manner in which the attaching portion 21 of the strap or belt is secured to the buckle frame is of particular value in connection with buckles embodying the present invention in that it permits the ready interchange of various straps for use with a single buckle. Plastic materials from which the buckle frame may be constructed may be obtained in various colors, and consequently attractive color schemes may be achieved. For example, a brown buckle may be associated with either a brown belt or a white belt, or a combination brown and white belt, and it will be apparent that the interchange of the belts may be achieved with a minimum of effort.

The embodiment of the invention shown in Figs. 4, 5, and 6 is in principle similar to the embodiment described above, except for the proportions of the bars and slots and for the manner in which the adjusting portion of the strap is attached thereto. In this embodiment, the side bars 30 and 31 are connected by end bars 32 and 33 and intermediate crossbars 34 and 35 to provide a narrow curved slot 36 similar to slot 16 of the previously described embodiment, a second slot 37, and a wide slot 38 similar to the slot 18 of the previous embodiment.

In this buckle the attaching portion 39 of the strap is secured to the crossbar 35 by wrapping the end of the strap about the crossbar and sewing it as indicated by the reference numeral 40. In order to accommodate conventional belts of the type having snap fasteners on the attaching end thereof, the intermediate crossbar 34 is provided with a notch 41, as shown best in Fig. 4, for permitting the snap fastener to pass between the crossbars 34 and 35 when the buckle is attached to the belt. In this embodiment of the invention the adjusting portion 43 of the belt is threaded through the frame in substantially the same manner as described in connection with Figs. 1, 2, and 3, and the clamping and adjusting action obtained is in all respects similar. It will be noted, however, that the slots 36 and 38 are spaced more closely than the slots 16 and 18, and consequently when stiff belts or straps are employed a somewhat greater degree of bulging at the portion of the strap which passes over the crossbars 34 and 35 may be encountered. As in the previously described embodiment, however,

the various crossbars are provided with front and rear walls inset from the front and rear surfaces of the side bars, so that the adjusting portion of the belt lies at least partially within the confines of the side bars throughout substantially the length of the buckle frame.

In the embodiment shown in Figs. 7 and 8, a similar arrangement of crossbars, end bars and slots is provided in a buckle frame 50, and for the purpose of securing the attaching portion 51 of the belt to the buckle frame, the intermediate crossbar 52 is provided with a finger or prong 53 which extends outwardly from the rear surface of the crossbar 52 adjacent the edge thereof. The attaching portion 51 of the strap is provided with an aperture 54 adapted to be engaged by the prong 53 when the attaching portion is threaded through the frame. As in the previously described embodiments, the adjusting portion 55 of the belt is threaded through the narrow curved slot and the wide slot of the frame so as to overlie the intermediate crossbars and underlie the sloping clamping surface of the end bar which defines the wide slot, thereby to provide the heretofore described non-slipping characteristics of the invention.

In the embodiment of the invention shown in Fig. 9, the side bars 60 and 61 of the buckle frame are connected by end bars 62 and 63 having inner curved side walls, and by crossbars 64 and 65 spaced to provide slots corresponding to the slots in the previously described embodiments. It will of course be understood that the various front and rear surfaces of the crossbars 62, 63, 64, and 65 are inset from the front and rear surfaces of the side bars in the same general manner as in the previously described embodiments, but in the structure shown in Fig. 9, the curved side wall 66 on the crossbar 64 is not concentric with the inner curved side wall of the end crossbar 62 but instead approaches the end bar at the ends thereof to provide a crescent-shaped slot or a slot having tapering ends. With this construction an additional holding force is provided, since the strap, when threaded through a slot of this character, will be pinched at the end portions of the slot and crimped toward the center of the slot. It has been found that the additional holding force provided by this further distortion of the belt in the curved slot is of particular advantage in connection with fabric belts, although it may be advantageously employed with belts of any desired character.

While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. A one-piece buckle for securing a strap in adjusted positions comprising a frame of molded material having spaced side bars connected by end and intermediate crossbars spaced to define strap-receiving slots therebetween, the adjacent side walls of two of said crossbars being curved to define an elongate arcuate slot extending across said frame, the front wall of one of said two crossbars being inset from the front surfaces of said side bars and meeting said curved side wall thereof in a sharp edge, the width of said slot being only slightly greater than

the thickness of the strap to be secured to permit the strap to be freely threaded therethrough and transversely curved by the opposed curved walls of said slot, said strap when tensioned in a direction parallel to the plane of said frame being sharply bent at a transversely curved portion thereof over said sharp edge, whereby slippage of said strap under tension relative to said frame is resisted by distortion of said strap in said slot and over said edge, said strap extending across the inset front wall of said one crossbar at least partially within the confines of the front surfaces of said side bars.

2. A one-piece buckle for securing a strap in adjusted positions comprising a frame of molded material having spaced side bars connected by end and intermediate crossbars spaced to define strap-receiving slots therebetween, the adjacent side walls of two of said crossbars being curved to define an elongate arcuate slot extending across said frame, the front wall of one of said two crossbars and the rear wall of the other of said two crossbars being respectively inset from the front and rear surfaces of said side bars and meeting said curved side walls in sharp edges, the width of said slot being only slightly greater than the thickness of the strap to be secured to permit the strap to be freely threaded therethrough and transversely curved by the opposed curved walls of the slot, said strap when tensioned in a direction parallel to the plane of the frame being sharply bent at transversely curved portions thereof over said sharp edges, whereby slippage of said strap under tension relative to said frame is resisted by distortion of said strap, the portions of said strap adjacent said slot extending across said inset front and rear walls of said two crossbars at least partially within the confines of the front and rear surfaces of said side bars.

3. A one-piece buckle for securing a strap in adjusted positions comprising a frame of molded material having spaced side bars connected by end and intermediate crossbars spaced to define strap-receiving slots therebetween, the inner side wall of one of said end bars and the adjacent side wall of an intermediate bar being curved to define an elongate arcuate slot extending across said frame, the front wall of said intermediate bar being inset from the front surfaces of said side bars and meeting said curved wall of said intermediate bar in a sharp edge, the width of said slot being only slightly greater than the thickness of the strap to be secured to permit the strap to be freely threaded through said slot and transversely curved by the walls thereof, said strap when tensioned in a direction substantially parallel to the plane of said frame being sharply bent over said edge at a transversely curved portion of said strap, whereby slippage of said strap under tension is resisted by distortion of said strap in said slot and over said sharp edge, said strap extending across the inset front wall of said intermediate bar at least partially within the confines of the front surfaces of said side bars.

4. A one-piece buckle for securing a strap in adjusted positions comprising a frame of molded material having spaced side bars connected by end and intermediate crossbars spaced to define strap-receiving slots therebetween, the inner side wall of one of said end bars and the adjacent side wall of an intermediate bar being curved to define an elongate arcuate slot extending across said frame, the front wall of said inter-

mediate bar and the rear wall of said one end bar being inset from the front and rear surfaces respectively of said side bars and meeting said respective curved side walls in sharp edges, the width of said slot being only slightly greater than the thickness of the associated strap to permit the strap to be freely threaded through said slot and transversely curved by the walls thereof, said strap when tensioned in a direction substantially parallel to the plane of said frame being sharply bent at transversely curved portions thereof over said sharp edges, whereby slippage of said strap under tension is resisted by distortion of said strap in said slot and over said edges, said strap extending across said inset front and rear walls of said intermediate and end bars at least partially within the confines of the front and rear surfaces of said side bars.

5. In combination with a strap having an attaching portion and an adjusting portion; a one-piece buckle comprising a frame having spaced side bars connected by end and intermediate crossbars spaced to define strap-receiving slots therebetween; one of said intermediate bars constituting a strap-attaching bar about which the 25 attaching portion of said strap extends so as to overlie the front wall thereof and extend rearwardly of the adjacent one of said end bars; another intermediate bar and the other end bar having the opposed side walls thereof curved to define an elongate arcuate slot extending across 30 said frame for receiving the adjusting portion of said strap; said adjusting portion when threaded through said buckle passing rearwardly of said other end bar, through said curved slot, in front of said intermediate bars so as to overlie the attaching portion across said attaching bar, and then between said attaching portion and the rear wall of said one end bar; the width of 35 said curved slot being only slightly greater than the thickness of said adjusting portion of said strap to permit said adjusting portion to be freely threaded therethrough and transversely curved by the opposed curved walls of said slot; said adjusting portion of said strap when tension is applied to said strap portions in a direction substantially parallel to the plane of said frame being bent over the curved edges of said slot at transversely curved portions of said strap and being clamped by said attaching portion against 40 said rear wall of said one end bar; whereby slippage under tension of said adjusting portion relative to said frame is resisted by distortion of said adjusting portion in said slot and over the edges thereof and by frictional clamping engagement with said attaching portion and said one end bar.

6. In combination with a strap having an attaching portion and an adjusting portion; a one-piece buckle comprising a frame having spaced side bars connected by end and intermediate crossbars spaced to define strap-receiving slots therebetween; one of said intermediate bars having the front wall thereof inset from the front surfaces of said side bars by at least the thickness of said strap and constituting a strap-attaching bar about which the attaching portion of said strap extends so as to overlie said inset front wall and extend rearwardly of the adjacent one of said end bars; another intermediate bar having its front wall inset from said front surfaces of said side bars less than said attaching bar; said other intermediate bar and to the other end bar having the opposed side walls thereof curved to define an elongate arcuate slot extend-

ing across said frame for receiving the adjusting portion of said strap; said respective front and rear walls of said other intermediate and end bars meeting said curved side walls in sharp edges; said adjusting portion of said strap when threaded through said buckle passing rearwardly of said other end bar, through said curved slot, in front of said intermediate bars so as to overlie the attaching portion across said attaching bar, and then between said attaching portion and the rear wall of said one end bar; the width of said curved slot being only slightly greater than the thickness of said adjusting portion of said strap to permit said adjusting portion to be freely threaded therethrough and transversely curved by the opposed curved walls of said slot; said adjusting portion of said strap when tension is applied to said strap portions in a direction substantially parallel to the plane of said frame being sharply bent over the curved edges of said slot at transversely curved portions of said strap, tightly pressed against said attaching portion over said attaching bar and clamped by said attaching portion against said rear wall of said one end bar.

7. In combination with a strap having an attaching portion and an adjusting portion; a one-piece buckle comprising a frame having spaced side bars connected by end and intermediate crossbars spaced to define strap-receiving slots therebetween; said end bars having the rear walls thereof inset by substantially the thickness of the strap from the rear surfaces of said side bars; one of said intermediate bars having the front wall thereof inset by at least the thickness of said strap from the front surfaces of said side bars and constituting a strap-attaching bar about which the attaching portion of said strap extends so as to overlie said inset front wall and extend rearwardly of the adjacent one of said end bars; another intermediate bar having its front wall inset from said front surfaces of said side bars less than said attaching bar; said other intermediate bar and the other end bar having the opposed side walls thereof curved to define an elongate arcuate slot extending across said frame for receiving the adjusting portion of said strap; said respective front and rear walls of said other intermediate and end bars meeting said curved side walls in sharp edges; said adjusting portion of said strap when threaded through said buckle passing rearwardly of said other end bar, through said curved slot, in front of said intermediate bars so as to overlie the attaching portion across said attaching bar and then between said attaching portion and the rear wall of said one end bar; the width of said curved slot being only slightly greater than the thickness of said adjusting portion of said strap to permit said adjusting portion to be freely threaded therethrough and transversely curved by the opposed curved walls of said slot; said adjusting portion of said strap when tension is applied to said strap portions in a direction substantially parallel to the plane of said frame being sharply bent over the curved edges of said slot at transversely curved portions of said strap, tightly pressed against said attaching portion over said attaching bar and clamped by said attaching portion against said rear wall of said one end bar.

of said one end bar; whereby slippage under tension of said adjusting portion relative to said frame is resisted by distortion of said adjusting portion in said slot and over the sharp edges thereof and by frictional engagement with said attaching portion and clamping engagement with said one end bar; said adjusting portion passing rearwardly of said end bars and said attaching portion passing in front of said attaching bar lying substantially within the confines of the front and rear surfaces of said side bars.

8. In combination with a strap having an attaching portion and an adjusting portion; a one-piece buckle comprising a frame having spaced side bars connected by end and intermediate crossbars spaced to define strap-receiving slots therebetween; one of said intermediate bars constituting a strap-attaching bar about which the attaching portion of said strap extends so as to overlie the front wall of said bar and extend rearwardly of the adjacent one of said end bars; another intermediate bar and the other end bar having the opposed side walls thereof curved to define an elongate arcuate slot extending across said frame for receiving the adjusting portion of said strap; said adjusting portion when threaded through said buckle passing rearwardly of said other end bar, through said curved slot, in front of said intermediate bars so as to overlie the attaching portion across said attaching bar and then between said attaching portion and the rear wall of said one end bar; said curved side walls converging adjacent the side bars of said frame whereby the width of said curved slot gradually decreases from a maximum width only slightly greater than the thickness of said adjusting portion of said strap; said adjusting portion when threaded through said curved slot being pinched at the edges thereof and crowded toward the center of said curved slot while being transversely curved by the opposed curved walls of said slot; said adjusting portion of said strap when tension is applied to said strap portions in a direction substantially parallel to the plane of said frame being bent over the curved edges of said slot at transversely curved portions of said strap and being clamped by said attaching portion against said rear wall of said one end bar; whereby slippage under tension of said adjusting portion relative to said frame is resisted by distortion of said adjusting portion in said slot and over the edges thereof and by frictional clamping engagement with said attaching portion and said one end bar.

9. In combination with a strap having an attaching portion and an adjusting portion; a one-piece buckle comprising a frame having spaced side bars connected by end and intermediate crossbars spaced to define strap-receiving slots therebetween; said intermediate bars defining a slot therebetween for receiving said attaching portion of said strap; one of said intermediate bars constituting a strap-attaching bar and having a fixed prong of a length less than the thickness of said strap extending from a rear wall thereof for engaging a hole in said attaching portion adjacent the end thereof when said attaching portion is threaded through said slot and about said strap-attaching bar so as to overlie the front wall of said bar and extend rearwardly of the adjacent one of said end bars; another intermediate bar and the other end bar having the opposed side walls thereof curved to define an elongate arcuate slot extending across said frame for receiving the adjusting portion of said strap;

said adjusting portion when threaded through said buckle passing rearwardly of said other end bar, through said curved slot, in front of said intermediate bars so as to overlie the attaching portion across said attaching bar and then between said attaching portion and the rear wall of said one end bar; the width of said curved slot being only slightly greater than the thickness of said adjusting portion of said strap to permit said adjusting portion to be freely threaded therethrough and transversely curved by the opposed curved walls of said slot; said adjusting portion of said strap when tension is applied to said strap portions in a direction substantially parallel to the plane of said frame being bent over the curved edges of said slot at transversely curved portions of said strap and being clamped by said attaching portion against said rear wall of said one end bar; whereby slippage under tension of said adjusting portion relative to said frame is resisted by distortion of said adjusting portion in said slot and over the edges thereof and by frictional clamping engagement with said attaching portion and said one end bar.

10. In combination with a strap having an attaching portion and an adjusting portion, a one-piece buckle comprising a frame having spaced side bars connected by end and intermediate crossbars spaced to define strap-receiving slots therebetween; said intermediate bars defining a slot of a width substantially equal to the thickness of said strap, said attaching portion of said strap having an end of greater thickness for preventing movement thereof through said slot beyond a predetermined point; one of said intermediate bars constituting a strap-attaching bar about which the attaching portion of said strap adjacent said thick end extends so as to overlie the front wall of said bar and extend rearwardly of the adjacent one of said end bars; another intermediate bar and the other end bar having the opposed side walls thereof curved to define an elongate arcuate slot extending across said frame for receiving the adjusting portion of said strap; said adjusting portion when threaded through said buckle passing rearwardly of said other end bar, through said curved slot, in front of said intermediate bars so as to overlie the attaching portion across said attaching bar and then between said attaching portion and the rear wall of said one end bar; the width of said curved slot being only slightly greater than the thickness of said adjusting portion of said strap to permit said adjusting portion to be freely threaded therethrough and transversely curved by the opposed curved walls of said slot; said adjusting portion of said strap when tension is applied to said strap portions in a direction substantially parallel to the plane of said frame being bent over the curved edges of said slot at transversely curved portions of said strap and being clamped by said attaching portion against said rear wall of said one end bar; whereby slippage under tension of said adjusting portion relative to said frame is resisted by distortion of said adjusting portion in said slot and over the edges thereof and by frictional clamping engagement with said attaching portion and said one end bar.

11. A one-piece plastic buckle for securing a strap in adjusted positions comprising a frame having spaced side bars of a thickness greater than the thickness of the strap, said side bars being connected by end and intermediate bars of less thickness than said side bars, said end bars

having oppositely curved inner side walls and having the rear walls thereof inset from the rear surfaces of said side bars, the inset rear wall of one end bar meeting the curved side wall thereof in a sharp edge to provide a sharp distortion line for the strap, and the inset rear wall of the other end bar gradually merging into the curved side wall thereof to provide a broad clamping surface for the strap, one intermediate bar having a curved side wall spaced from the inner curved wall of said one end bar to define an arcuate slot of a width only slightly greater than the thickness of the strap and having its front wall inset from the front surface of said side bars and meeting the curved side wall thereof in a sharp edge, a second of said intermediate bars being spaced from said other end bar to provide a slot of sufficient width to receive plural thicknesses of said strap, said intermediate bars

5 having a slot therebetween for receiving an attaching portion of the strap at least partially encircling said second intermediate bar and passing through said plural thickness slot to underlie said clamping surface, whereby a strap having its attaching portion secured to and encircling said second intermediate bar and having its other end threaded through said curved slot from the rear of the frame and through said plural thickness slot from the front of the frame over the attaching portion of the strap will when subjected to tension be held against slipping relative to the frame by the distortion of the strap in said curved slot and over said sharp edges and by clamping engagement of the threaded portion of the strap between said clamping surface and said attaching portion of the strap.

PAUL W. WHITE.
